UNITED STATES PATENT OFFICE.

CHARLES A. STOCKSTROM AND LOUIS STOCKSTROM, OF ST. LOUIS, MO.

VAPOR-BURNER.

SPECIFICATION forming part of Letters Patent No. 350,086, dated September 28, 1886.

Application filed July 9, 1885. Serial No. 171,058. (No model.)

To all whom it may concern:

Be it known that we, CHARLES A. STOCKSTROM and LOUIS STOCKSTROM, of the city of St. Louis, in the State of Missouri, have invented a certain new and useful Improvement in Vapor-Burners, of which the following is a full, clear, and exact description, reference being had to the accompanying drawings, forming part of this specification, and in which—
10 Fig. 1 is a top view of our improved burner. Fig. 2 is a side elevation, part broken away. Fig. 3 is a vertical transverse section taken on line 3 3, Fig. 1, looking in the direction of the arrows. Fig. 4 is a vertical trans-
15 verse section taken on line 4 4, Fig. 1, looking in the direction of the arrows, the commingling-tube leading to the third burner being omitted. Fig. 5 is a horizontal section taken on line 5 5, Fig. 3, looking down. Fig. 6 is an enlarged detail section taken on line 6 6, Fig.
20 3. Fig. 7 is a detail section taken on line 7 7, Fig. 5. Fig. 8 is a top view illustrating a modified form of our preferred construction. Fig. 9 is a vertical transverse section taken
25 on line 9 9, Fig. 8, looking in the direction of the arrows. Fig. 10 is a similar view taken on line 10 10, Fig. 8, looking in the direction of the arrows. Fig. 11 is a section of one of the valve-stems, taken on line 11 11, Fig. 10, showing part of the rack and a pinion in side view. Figs. 1, 2, 3, 4, 8, 9, and 10 are on the same scale. Figs. 5, 6, 7, and 11 are on a larger scale.

Our invention relates to certain improvements of the class of vapor-burners in which a generator is used supplying gas to one or more burners; and our invention consists in features of novelty hereinafter fully described, and pointed out in the claims.

Referring to the drawings, A represents the body or frame of a gasoline or vapor stove, and B part of the supply-pipe.

C represents the burners, which may be two or more in number. (We have shown three.)

D represents the generator, and E the commingling-tubes leading from near the generator to the respective burners, as in the form referred to. The generator consists of a disk, F, around the periphery of which is a port or passage, G, (see Figs. 5 and 7,) with which the vertical pipe H, extending from or connected to the main supply-pipe, communicates. This

port communicates with a transverse port or passage, F', in the disk F, and connected with this latter port are pipes or tubes J, K, and L, provided with valves J², K², and L² (see Fig. 3) and jets J³, K³, and L³, and they are also preferably provided with needle-valves J⁴, K⁴, and L⁴, as shown. The jet of the pipe J is beneath a short vertical commingling-tube, M, that leads to the burner formed by the generator D and a perforated cap or cover, D'. The valve J² of this burner is operated by a lever, J⁵, connected thereto and extending upward and through a slot, A', in the 65 table of the stove.

Located near the jets K³ L³ of the pipes K L are the free or open ends of the commingling-tubes E, above mentioned, that communicate with the burners C, that are located away 70 from the generator. The gas and air enter these tubes, (when these last mentioned burners are used,) as shown by the arrows, Fig. 6, and the gas is turned on to supply these burners, and shut off by levers N, connected to the 75 valves K² and L² by rods N' and cranks N'. Each lever is pivoted beneath its burner at O and passes through slots A' in the top of the stove, the same as lever J⁵. We have shown one of the rods connected to its lever between 80 the pivot O and the end of the lever, and the other rod connected to the end of the lever that extends beyond the pivot. By this arrangement the levers are moved in the same direction to open or close both valves K² and 85 L², notwithstanding the valves project in opposite directions from the generator. Each burner thus has its own independent valve-lever, while but the one generator is used, which is much more convenient than having the levers of all the valves clustered together at the generator, as has been the practice heretofore. When it is desired to use either one of these burners that are located away from the generator, the lever located at such burner is 90 moved to turn on the supply the same as with burners of the usual form.

We have shown the tubes E supported by straps T, depending from beneath the top of the stove. The burners are shown as provided with arms V, by which they are connected to rings above them made fast to the top of the stove.

In Fig. 8 the generator is placed between

the outside burners, and the levers N are connected to the valves K² L² by racks U and pinions V, the levers in this case being turned or revolved instead of being swung on a pivot, 5 as in our preferred form.

It is not absolutely necessary to have a burner located at the generator, as we have shown, though we prefer to construct the stoves in this manner; nor is it necessary that 10 the form of lever shown, both as our preferred form and as a modification of the same, should be used, as any means to form a connection between each burner and the valve of that burner located at the generator could be used.

15 We claim as our invention—

1. The combination, with a gasoline-stove having a suitable burner, of a generator having a valve, a connecting-tube extending from the valve to the burner, an operating-rod in 20 proximity to the burner, and a rod or its equivalent for connecting the operating-rod at the burner to the valve-rod at the generator, substantially as set forth.

2. The combination, with a gasoline-stove having a plurality of burners, of a generator having a valve for each burner, conducting-tubes extending from the respective valves to the respective burners, an operating-rod for 25 and in proximity to each burner, and a rod or its equivalent for connecting the operating-

rods to their respective valve-rods located at the generator, substantially as and for the purpose set forth.

3. The combination, with a burner, of a generator having a valve, a commingling-tube 35 extending from the valve to the burner, a crank-arm on the valve-stem, a lever in close proximity to the burner, and a rod connecting the crank-arm and lever, substantially as set forth.

4. The combination, with burners, of a generator having valves provided with crank-arms, independent levers in proximity to the burners, independent commingling-tubes extending from the burners to their respective 45 valves, and rods connecting the levers with their respective crank-arms, substantially as set forth.

5. The generator for a vapor-burner, comprising a supply-pipe, disk F, having port or 50 passage G around the periphery, and transverse port or passage F', valves having tubes J K L connecting with said transverse port or passage, and a perforated cap or cover, D, substantially as set forth.

CHAS. A. STOCKSTROM.

LOUIS STOCKSTROM.
